HYDRAULIC DEVICE AND TRAVEL LIMIT VALVE

Louis J. Lencioni, Menlo Park, Calif., assignor to Lawrence H. Cook, doing business as Cook Research Laboratories, Menlo Park, Calif.

Application July 10, 1953, Serial No. 367,257

1 Claim. (Cl. 121—38)

This invention relates to a hydraulic device and has for its principal object the provision of a simple, reliable and economical travel limit valve in such device for automatically limiting the travel of the fluid pressure actuated plunger that is connected with any suitable tool or other means for doing work.

Another object of the invention is the provision of a fluid pressure actuated shear having means therein for automatically stopping the actuation of the shear at the moment it has finished a cutting operation and before any objectionable strain is put on the mechanism by reason of the force exerted by the fluid.

A still further object of the invention is the provision of a safety means in a hydraulically actuated, or fluid actuated device to prevent objectionable and injurious strains on the mechanism by reason of the fluid pressure employed to actuate the device; and a still further object of the invention is the provision of a travel limit valve that may be quickly regulated to control the degree of travel of the fluid actuated plunger in a fluid pressure actuated device.

In fluid pressure actuated shears, such as a cable cutter of the type illustrated in the drawings, it has been customary to provide a manually actuated valve for relieving the pressure in a fluid pressure actuated cylinder as soon as the cable is cut, thus insuring against excessive pressure building up, and also enabling the plunger to be returned under action of a spring. If the valve is not actuated soon enough, excessive pressure will develop, and if actuated too quickly, the cut may not be completed. A pressure relief valve is usually provided, but as such valves are dependent upon a predetermined fluid pressure beyond that required to effect a completion of the cutting operation, an excess of pressure will still be created, assuming the valve operates as intended. There is always the possibility of pressure relief valves sticking or failing to operate, particularly where they may go for long periods of time without being actuated.

With the present invention, the fluid pressure in the cylinder is automatically relieved each time the plunger makes a working stroke, and the pressure will not be relieved until such stroke is completed. In other words, the pressure variations in the cylinder have no effect when the pressure is relieved, but such relief is dependent upon the plunger travelling a predetermined distance, and each time it travels such distance, the pressure will be relieved.

Other objects and advantages will appear in the description and in the drawings.

In the drawings,

Fig. 1 is a vertical sectional view through a fluid pressure actuated device showing the invention, the device being shown in starting position before actuation thereof.

Fig. 2 is a fragmentary sectional view showing the device at the completion of its stroke when the pressure is relieved.

Fig. 3 is a fragmentary sectional view of the invention modified for a hand operated device.

In detail, the apparatus shown is a shear for cutting

2

cable and the like and is shown to illustrate one application of the invention.

In the device or machine illustrated, a cylinder 1 is provided, having a head 2 at one end, and a plug 3 is supported within said cylinder for reciprocable movement axially of the latter.

The end of the cylinder opposite head 2 is provided with a removable head 4 that, in turn is formed with an opening for passage therethrough of an extension 5 of said plunger. This extension is pinned to a cutter blade 6 having a cutting edge 7 at its end and which blade is movable across space 8 and to between a pair of cutting blades 9. The cable to be cut is normally positioned in space 8 and when the cutting edge of blade 6 moves beyond the cutting edges of blades 9 the cut will be completed. No claim is made to the foregoing structure, all of which is shown in United States Letters Patent No. 2,384,130 of September 4, 1945.

An outer wall 12 surrounds the cylinder 1 in spaced relation thereto, and the head 2 extends past the cylinder at 13 to said wall with which it may be integral. The end of the space between the wall 12 and the cylinder that is opposite wall 2 is closed by wall 14. Thus a chamber 15 for oil is provided around the cylinder 2.

At the side of wall 2 (and its extension 13) that is opposite the cylinder 1 is an oil supply chamber 16 having a bottom wall in continuation of the bottom part of wall 12, and an end wall 17 in spaced opposed relation to head 2, and a top wall 18.

The lower portion of the extension 13 of head 2 is formed with an opening 20 to provide a communication between chambers 15, 16 and said chambers normally contain oil, which is omitted in the drawings for purpose of clarity.

Supported on the top wall 18 of chamber 16 is a motor 22 that is connected with a conventional pump 21, the intake of which is submerged in the oil in said chamber.

The pump outlet communicates with the space between the head 2 and the plunger 3 by pipe 23 which extends to inlet 24 in said head, and a pre-set relief valve 25 carried by head 2 also communicates with said space.

The plunger 3 is normally held adjacent to head 2 by means of a relatively heavy coil spring 26 that reacts between said plunger and the head 4. Said latter head is preferably removable, being held in position by several stud bolts 27.

As already mentioned, the plunger 3 is provided with an axial extension 5 that is integral therewith, and an axially elongated recess 28 formed in said extension opens outwardly of the plunger centrally thereof. A sleeve 29 is threadedly secured within said recess at the open end of the latter, which sleeve has a head 30 projecting from the plunger for engagement with the head 2 when the plunger is at the end of its stroke nearest said head 2.

The head 2 is formed with a discharge opening 31 which is preferably smaller than the bore in sleeve 29, but which opening is coaxial with said bore.

A rod 33 is relatively loosely positioned within the recess 28 and the bore of sleeve 29. A coil spring 34 reacts between the closed end of recess 28 and said rod to urge said rod outwardly of the open end of said recess. Insofar as this invention is concerned the bore in sleeve 29 is part of recess 28, but by using a sleeve, as described, its inner end provides an axially facing shoulder 35 that is directed toward the closed inner end of the recess 28.

The length of rod 33 is such that, when spring 34 is compressed and the plunger is at the end of its stroke nearest the head 2, the outer rounded end of the rod will seat against the edges of aperture 31 closing the latter. Thus rod 33 becomes a valve element and oil pumped into the space 40 between the plunger 3 and head 2 will cause the plunger to move away from said head.

The spring 34 will retain the valve element in a position closing outlet 31 as the plunger moves away from head 2, and it will hold the valve element in said position until the plunger has moved to the position immediately prior to that shown in Fig. 2 and at which position the cable has been completely severed. When said position has been reached, a collar or projection 41 on the rod 33 will be engaged by the shoulder 35 in recess 28 and will pull the rod away from the discharge opening 31 thereby relieving the pressure in chamber 41 and consequently removing any likelihood of forcing the head 4 off the cylinder or breaking or injuring any of the other parts of the machine.

The cylinder 1 is formed with a second opening 43 that, in turn, is closed by a ball 44. Ball 44 is held in position tightly closing opening 43 by a rod 45. Rod 45 is threaded in an opening in wall 12 and upon rotating said rod manually by actuation of handle 46 the ball 44 will be moved to permit the oil in space 40 to pass through opening 43 into chambers 15, 16 when the pump is stopped. Spring 26 is effective for forcing the oil out of the cylinder by moving plunger 3 back to the position shown in Fig. 1.

From the foregoing, it will be obvious that no possible damage can be caused by failure of the relief valve 25 or by failure of the operator to open valve 44 or by failure of the operator to stop the motor or pump, since the pressure in space 40 cannot build up beyond the degree necessary to move the plunger a distance sufficient to open valve 33. The rod 33 will be called a valve or valve element since that is the function it performs.

In the form of the invention as seen in Fig. 3, the rotary power actuated pump is not employed, but instead, the plunger 50 is reciprocated manually oscillating the handle 51, thus drawing fluid from reservoir 52 through duct 53 past check valve 54 and below said plunger upon the upstroke of the latter.

Upon the down stroke of plunger 50, the fluid is forced into duct 55 which opens into the cylindrical bore 56 in which the plunger or piston 58 that is connected with the cutting blade is reciprocable.

In the case of the power actuated device, the pressure inlet was offset to one side of the discharge outlet 31, but in the present instance the port or opening 60 at the end of duct 55 is both the inlet and outlet and the valve element 59 (which is identical with the element 33 of Figs. 1, 2) closes said opening.

In operation, in the case of Fig. 3, as soon as the piston or plunger 58 has been moved to the position of plunger 3 in Fig. 2 no further power can be applied since the fluid will merely move back and forth in duct 55 with each reciprocal movement of plunger 50, with valve 54 remaining closed.

This particular form of the invention is the most commonly employed since the hand operated device has a more general use.

I claim:

In combination with a single, stationary cylinder having a first head at one end thereof and a plunger recip-

rocable within said cylinder with a space between said head and said plunger for liquid under pressure; a second head at the end of said cylinder opposite to said first head and said plunger having an extension of reduced diameter rigid therewith slidably extending through said second head, a spring around said extension reacting between said plunger and said second head for yieldably urging said plunger toward said first head and said second head including a portion in opposed relation axially of said cylinder to said plunger for holding said plunger in said cylinder, an outlet in said first head coaxial with said plunger and a valve element supported on said plunger in axial alignment with said outlet for movement relative thereto, a spring reacting between a portion of said plunger and said element for yieldably urging said element to a position closing said outlet during movement of said plunger to a predetermined point away from said first head, an inlet in said first head for admitting liquid under pressure into said space, means respectively on said plunger and on said element movable into engaging relation upon movement of said plunger to and past said point for moving said element away from said outlet upon movement of said plunger past said point thereby opening said outlet, an outer wall enclosing said cylinder spaced therearound and connected with said first head and with said second head to provide a closed chamber for liquid around said cylinder, a conduit for oil communicating between said cylinder and said inlet and outlet a portion of which conduit comprises said chamber and said inlet and said outlet, an opening formed in said cylinder adjacent to said head communicating with said chamber, a valve element carried by said outer wall movable into and out of position closing said last mentioned opening for admitting liquid from said cylinder into said chamber and conduit upon actuation of said last mentioned element for movement to open position and means connected with said last mentioned element accessible from outside said wall for manual manipulation thereof, said inlet and said outlet being a common opening and said first mentioned valve element being a check valve in said conduit adapted to be intermittently opened upon liquid pressure in said conduit being greater than liquid pressure in said cylinder.
